SUPPORT STAND FOR A BATTERY OPERATED TOOL

Harold S. Foster, Huntington Beach, Charles J. Ortega,
Valencia, and Alvis R. Knowles, Carson, Calif., as
signors to Eldon Industries, Inc.

Filed Aug. 27, 1973, Ser. No. 391,790

Term of patent 14 years

Int. Cl. D8—05

U.S. Cl. D8—71

FIG. 1 is an isometric view of a support stand for a battery operated tool embodying the new design of our invention;

FIG. 2 is a side elevational view thereof;

FIG. 3 is a top plan view thereof;

FIG. 4 is a bottom plan view thereof;

FIG. 5 is a rear elevational view thereof; and

FIG. 6 is a front elevational view thereof.

We claim:

The ornamental design for a support stand for a battery operated tool, substantially as shown and described.
